US00D939644S

(12) **United States Design Patent** (10) **Patent No.:** **US D939,644 S**
(45) **Date of Patent:** **** Dec. 28, 2021**

(54) **REHABILITATION DEVICE**

- (71) Applicant: **ROM TECHNOLOGIES, INC.**,
Brookfield, CT (US)
- (72) Inventors: **Samuel Marcus Ach**, Portland, OR
(US); **Doug Golenz**, Littleton, CO (US)
- (73) Assignee: **ROM TECHNOLOGIES, INC.**,
Brookfield, CT (US)
- (**) Term: **15 Years**
- (21) Appl. No.: **29/764,081**
- (22) Filed: **Dec. 28, 2020**

Related U.S. Application Data

- (62) Division of application No. 29/717,404, filed on Dec. 17, 2019, now Pat. No. Des. 907,143.
- (51) **LOC (13) Cl.** **21-02**
- (52) **U.S. Cl.**
USPC **D21/663**
- (58) **Field of Classification Search**
USPC D21/419, 432, 435, 667, 666, 668, 690,
D21/676, 691, 662, 675, 686, 694, 663,
D21/697; D6/552; D12/108, 109, 111,
D12/112, 113, 124, 178, 345

(57) **CLAIM**

The ornamental design for a rehabilitation device, substantially as shown and described.

DESCRIPTION

FIG. 1 is a top isometric view of a first embodiment of a rehabilitation device.

FIG. 2 is a front view of the device of FIG. 1.

FIG. 3 is a rear view of the device of FIG. 1.

FIG. 4 is right side view of the device of FIG. 1.

FIG. 5 is a left side view of the device of FIG. 1.

FIG. 6 is a top view of the device of FIG. 1.

FIG. 7 is a top isometric view of a second embodiment of a rehabilitation device.

FIG. 8 is a front view of the device of FIG. 7.

FIG. 9 is a rear view of the device of FIG. 7.

FIG. 10 is right side view of the device of FIG. 7.

FIG. 11 is a left side view of the device of FIG. 7; and,

FIG. 12 is a top view of the device of FIG. 7.

The dashed lines form no part of the claimed design.

1 Claim, 12 Drawing Sheets
